KNITTED FABRIC AND METHOD OF
MAKING THE SAME

Edward Samuel Barsby and Alfred Percy Saunders, Leicester, England, assignors to Wildt and Company Limited, Leicester, England, a British company

Application June 2, 1949, Serial No. 96,796
In Great Britain June 17, 1948

5 Claims. (Cl. 66—183)

1

This invention relates to knitted fabric, and has reference particularly to machine produced fashioned knitted fabric wherein the number of loops vary from course to course suchwise as to reduce or/and increase the number of wales and thereby shape the fabric by narrowing or/and widening it.

The expression "knitted fabric" is used herein in a generic sense to include not only machine produced fashioned fabric in the piece for subsequent making up into articles and garments, but also complete fully-fashioned articles and parts thereof. In this connection, for instance, the invention may be applied to hose blanks, and also include within its scope fully-fashioned stockings and other articles of hosiery.

Now heretofore when progressively reducing the number of knitted wales in fabric the selvedge loops at each narrowing or "fashioning" have usually been transferred to and interknitted with loops in adjoining wales. In practice, a succession of end loops has been transferred in this way at each side of the fabric, and these transfers have resulted in the production of thickened stitches or "fashion marks." The object of transferring selvedge loops in this manner is, of course, to prevent running back, since otherwise each cast-off loop, being unsupported, would release the previously knitted loop and that, in turn, other loops of the same wale. For widening knitted fabric, several methods have heretofore been available. For instance, there is the method of widening involving the employment of two yarn carriers which feed in two separate yarns and are so controlled that one traverses beyond the other at each edge of the fabric being widened. In this case, however, the empty needle beyond the additional needle or needles introduced to knit at each end of the series of needles during a widening operation holds at least one of the yarns to be knitted, thereby providing a supporting loop enabling the said additional needle or needles successfully to clear and knock over the additional loop or loops at the selvedge. But, as is well known to those acquainted with the art concerned, such conventional methods of making fashioned fabric by narrowing or/and widening, involve unproductive movements and operations in the machines upon which the fabric is knitted. In certain cases, as much as 10% of the productive time per article or garment is lost.

One of the objects of the present invention is to obviate the foregoing disadvantages of, and difficulties encountered in, previous methods of

2

making machine produced fashioned fabric by an improved method resulting in the production of satisfactorily locked selvedges, without transference of knitted loops, as knitting proceeds.

Another object is to enable a fully-fashioned hose blank to be knitted by commencing with a welt, thereafter proceeding with fashioning, including narrowing, with a safe selvedge, and ultimately finishing at the toe.

10 Broadly considered, the improved method of making shaped flat knitted fabric consists in knitting a web with at least one yarn, varying the number of knitted loops in different courses suchwise as to narrow or/and widen the fabric, and incorporating wale threads in knitted loops at opposite ends of the said courses suchwise that, as knitting proceeds, the said threads are interlooped with knitted loops in the corresponding end wales to form locked, i. e. run-resisting, 20 selvedges.

Preferably, a single wale thread is caused to be incorporated in a knitted loop or loops at each end of each of the appropriate courses, although it is also within the scope of the invention to 25 incorporate two or more separate wale threads in a corresponding number of adjoining individual knitted loops at each end of each of the said courses.

The wale threads may advantageously be 30 wrapped around appropriate needles by conventionally operated wrap thread feeders so that the said threads, when wrapped, and knocked over, without being knitted, become looped around and between the legs or sides of the knitted loops at 35 the selvedges. Thus, where latch needles are employed, the wale threads would be wrapped around the stems of the needles below the latches, whereas in the case of bearded needles, the said threads would be wrapped either around the beards, or below the beards in which latter instance the beards would require to be pressed. As will be appreciated, if a single wale thread is 40 wrapped around individual needles the thread will be looped around and engage both legs or sides of the corresponding single selvedge needle loops. If, on the other hand, by the procedure now well known as multi-needle wrapping, a single wale thread is wrapped around, say, two adjoining end needles, then the thread will, of course, be looped around and engage only the outer legs of sides of the corresponding pairs of needle loops at the selvedge. In either event, the or each wale thread will also pass through the appropriate needle loops.

Accordingly, when narrowing fabric by the

improved method, the cast-off loops at the ends of each course where narrowing takes place will be locked or tied in by the wale (wrap) thread interlooped therewith. In this connection, therefore, the invention provides an improved and efficient method of narrowing, enabling knitting on the narrowing needles progressively taken out of action to be safely discontinued without transference of the terminal loops. As far as widening is concerned, the presence of wrapped loops of wale threads upon the initially empty endmost needles progressively introduced into the series of needles facilitates the clearing of the first needle loops "picked up." In this way the formation of loose selvedges, during widening, is effectively prevented.

In making the improved fashioned fabric, narrowings or/and widenings may take place regularly and progressively either course by course, or at intervals of two or more courses.

The basic structure of the improved fashioned fabric may be knitted from a single ground yarn alone, or from such a ground yarn in conjunction with an auxiliary yarn such as a splicing or a plating yarn. Moreover, the fabric may consist either of a plain knitted web or of a web patterned or ornamented by stitch variation.

In order that the invention may be more clearly understood and readily carried into practical effect, a specific example of the improved machine produced fashioned fabric and typical hose blanks incorporating such fabric will now be described with reference to the accompanying drawings, wherein:

Figure 1 is a portion of such fashioned fabric, drawn to an enlarged scale, showing one of the ways of producing a locked selvedge by locking the endmost knitted loop only in every course,

Figure 2 is a similar view showing how a locked selvedge is produced by locking the two endmost knitted loops in every course,

Figure 3 is a detail view illustrating a modification of the fabric shown in Figure 2,

Figure 4 shows a flat hose blank to which the invention may be applied, and

Figure 5 illustrates a hose blank produced on a circular hose knitting machine.

Like parts are designated by similar reference characters throughout the drawings.

In Figure 1 is shown a shaped or fashioned machine produced knitted web comprising courses each composed of alternate knitted loops 1 and intervening sinker loops 2 knitted in a coursewise reciprocatory manner. The alternate courses as successively knitted are indicated by the letters, a, b, c, d, e, f and g. At the course a the fabric is narrower than at the course b to the extent of one knitted loop, the fabric being progressively widened, one loop per alternate course to the course d from which the fabric is then progressively narrowed, again to the extent of one loop per alternate course to the course g. To lock the endmost knitted loops 1 in all of the courses and produce a run-resisting selvedge a wale thread 3 is interlooped with the said loops. As will be seen, in the widened portion of the fabric, including the alternate courses a-d, the wale thread 3 is wrapped around the legs 4 and 5 of the endmost knitted loop 1 in each of said alternate courses. The loops 6 constituted by the wrapped portions of the wale thread 3 appear on the inside faces, i. e. the back, of the fabric. In the narrowed portion of the fabric, that is to say the portion including the alternate courses e, f and g, the wale thread

3 is wrapped round the legs 4 and 5 of the knitted loops 1 in every course, the cast-off loops 1a in the courses e, f and g being locked by the run-resisting loops 6. In making the fabric just described, the wale thread 3 is not knitted by the needles: the wrap loops 6 are taken below the latches, in the case of latch needles being used, and, in the case of bearded needles, the thread 3 is either wrapped on the beards, or wrapped below the beards in which latter event the beards are pressed, thereby causing the wrap loops 6 to appear on the back of the fabric and to engage the legs 4 and 5 of all of the endmost knitted loops 1. As a consequence, the wrap thread 3 extends from points at the back of the fabric between the legs 4 and 5 of the knitted loops 1 so that the cast-off loops a in the narrowed portion of the fabric are held by the run-resisting loops 6.

The fabric shown in Figure 2 is in all essential respects similar to that depicted in Figure 1, the only difference being that the wale thread 3 is incorporated in the two endmost wales in every course. In this case, the thread 3 is looped around and engages only the outer legs 5 of the endmost knitted loops 1 and the inner legs 4 of the adjacent knitted loops. This strengthens the selvedge and tends to prevent its curling.

In the modification shown in Figure 3, the wrap thread 3 is wrapped at the alternate courses a, b, c, d, e, f and g only.

The improved fashioned fabric may be produced on a straight bar machine, in which instance the conventional side transfer combs would be replaced by wrap feeders adapted for operation at the ends of the series of needles suchwise as to supply wale threads to and wrap them around appropriate end needles. On such a machine, a fully-fashioned stocking blank such as that shown in Figure 4 can be expeditiously knitted. This blank is commenced at the welt 7 and ends at the toe 15. A wrap thread is incorporated either throughout or in appropriate portions of the two selvedges. The particular flat hose blank illustrated comprises, in order of knitting, the welt 7, thigh narrowings 8, a leg 9, calf 10, ankle 11, widened heel portions 12, narrowed heel portions 13, instep 14, toe 15.

Alternatively, the fabric may be made on any suitable circular knitting machine adapted to operate with rotary reciprocatory, as well as with circular, motion: in this case, wrap feeders would be mounted and adapted for operation within the range of the ends of the arcuate group of needles upon which fabric is knitted in a coursewise reciprocatory manner. On a seamless hose machine it is accordingly possible, by the adoption of the improved method, to produce a fully-fashioned stocking blank commencing at the welt and then producing, by reciprocatory knitting, a true fully-fashioned portion with a locked selvedge at each side thereof. It is also possible to produce a fully-fashioned stocking blank such as that shown in Figure 5 commencing at the welt 16 and knitting both this and the upper leg portion 17 by circular knitting and then proceeding by knitting in a coursewise reciprocatory manner, meanwhile narrowing the blank at 18 to the ankle 19, and then knitting the heel 20, foot 21 and toe 22. Either of these procedures, rendered possible by safe narrowing as hereinbefore described, without loop transference, therefore enables the hose blank to be made with an automatic welt. Heretofore, part circular, part

reciprocatory knitted hose blanks have usually had to be commenced at the toe and progressively widened, and as a consequence they could not be made with an automatic welt.

The invention also includes, as features, fashioned fabric, articles, garments and parts thereof made in accordance with the improved method. In this connection one such feature comprises a knitted fabric having selvedges and wherein the needle loops in different courses vary in number, appropriate ones of the said loops at each selvedge being locked in and prevented from running back by means of at least one additional thread which is incorporated walewise and intermeshed with the knitted web.

The improved machine produced fashioned fabric may be made on any knitting machine having either a straight or an arcuate needle bar furnished with fixed needles, or on any appropriate type of machine equipped with independently operable latch needles.

What we claim then is:

1. A selvedged knitted fabric comprising a web of knitted loops of which those in different courses vary in number so as to shape the fabric, and, at opposite ends of said courses, wale threads which are wrapped around and, at the back of the fabric, extend between the sides of knitted loops in the end wales to form run-resisting selvedges.

2. A selvedged knitted fabric at least a portion of which is narrowed and has cast-off knitted loops at the ends of courses comprising progressively diminishing numbers of knitted loops, and wale threads, portions of which are wrapped around and, at the back of the fabric, extend between the sides of the said cast-off knitted loops so that the latter are prevented from running back.

3. A fully-fashioned stocking blank the selvedges of which, in contra-distinction to having therein transferred knitted loops, are locked and made run-resisting by the incorporation therein of wale threads, the selvedges being locked by

wale threads which are wrapped around and, at the back of the blank, extend between the sides of the knitted loops in the end wales.

4. A fully-fashioned stocking blank comprising a welt, a circular knitted upper leg portion, a following fully-fashioned portion produced by reciprocatory knitting, and the knitted loops of which vary in number in different courses, and threads which are incorporated walewise into the selvedges of the said fully-fashioned portion suchwise as to be wrapped around and, at the back of the fabric, extend between the sides of the knitted loops in the end wales to form run-resisting selvedges.
5. A method of making knitted fabric which consists in knitting a web with at least one yarn, varying the number of knitted loops in different courses such wise as to shape the fabric, and incorporating wale threads in knitted loops at opposite ends of said courses suchwise that, as knitting proceeds, the said threads are wrapped around and, at the back of the fabric, extend between the sides of the knitted loops in the end wales to form run-resisting selvedges.
